UNITED STATES PATENT OFFICE.

WILLIAM E. JACOBS AND HENRY L. JACOBS, OF COLUMBUS, OHIO.

ROAD-SCRAPER.

SPECIFICATION forming part of Letters Patent No. 254,137, dated February 28, 1882.

Application filed December 18, 1880. (No model.)

To all whom it may concern:

Be it known that we, WILLIAM E. JACOBS and HENRY L. JACOBS, citizens of the United States, residing at Columbus, in the county of 5 Franklin and State of Ohio, have invented a new and useful Improvement in Road-Scrapers, of which the following is a specification.

The nature of our invention consists, first, in a scraper-bowl provided with handle-loops of 10 peculiar construction, through which the handles may slide, and by which the handles may be fastened and held from sliding, as herein-after described; second, in a scraper having sliding handles so arranged as to allow the 15 bowl of the scraper to revolve with the handles through the bail.

Figure 1 in the accompanying drawings is a perspective view of a road-scraper provided with our improvements; and Figs. 2, 3, 4, 5, and 20 6 are side elevation diagrams, showing the scraper in five different positions in which it appears while it is filling with dirt and dumping the same.

A represents the bowl, B the handles, and C 25 the bail, of a road-scraper.

The bail C, as usual, is hinged at a to the sides of the bowl; and the bowl B, as usual, is provided with a spur, D, which acts as a "grab" to take into the earth, and thereby insure a revolution of the bowl in the act of dumping a load of dirt which has been collected by the bowl. This grabbing-spur is fastened to the upper portion of the back of the bowl, and it may be in the middle line of the bowl, or there may be 30 two such spurs—one on either side of such middle line of the bowl.

To the upper edge of each side of the bowl, and in rear of the pivot of the hinge a of the bail, an oblong loop, E, is applied, as shown. 40 The loops E E are formed of strong plate metal bent into nearly an inverted-U form, so as to have bolting or riveting extensions e provided upon the portions which form the loops proper. The extensions e are swaged or drawn down to 45 the form of the inner and outer surfaces of the bowl at the portions where they bear against the bowl, and by this means the shoulders e' are formed between the loops proper and their extensions e. The loops E E thus formed are 50 fastened to the scraper-bowl in any suitable manner—say by rivets or brazing material.

To the loops E E scraper-handles may be permanently fastened by inserting the ends of the handles into the loops and passing a suitable confining device through the sides of the loops and through the handle; but the greatest utility of the loops E E is developed when the handles B are constructed to slide in the loops, as shown in the drawings. The handles, when constructed to slide, are formed with 55 spurs b on their inner ends, said spurs standing upward and at right angles, or nearly so, with the handles proper. The spurs b serve as stops to prevent the handles getting too far back and out of the loops, and they also serve for engaging with the earth during a certain stage of the 60 operation of the scraper, as will be presently described.

Stop-pins b' on the handles also serve to prevent the handles slipping out of the loops. 70

By referring to Fig. 2 it will be seen that the scraper is in an upright position, or ready for filling, the handles being set backward to their full length. In this position the scraper is drawn forward by its bail in the direction of 75 the arrow until the bowl is filled and ready for dumping the load. Now the handles with the bowl are lifted up, and with the aid of the team the bowl and handles are turned over, as shown in Fig. 3, and thus turned over the spurs on the handles engage in the earth, and the team being driven onward and the bowl drawn forward, the bowl and handles will occupy the positions shown in Fig. 4, and the handles can pass through the bail C, as shown in said figure. At this stage the grabbing-spur D will engage in the earth and turn over the bowl, as 80 shown in Figs. 5 and 6, and thus turned over the scraper is drawn again to the place for filling it with earth, and the operator takes hold of the handles and pulls them back until the spurs b strike the loops E, as shown in Fig. 2. 85

The handles may be drawn back by springs; but for simplicity in the construction of the scrapers we prefer to leave off such springs. So, 90 also, might spring-catches be provided on the loops E or handles B, for the purpose of making the handles permanent, instead of sliding, at such times as permanency in the handles may be desired. 95

The handle-loops form a simple, strong, and 100 cheap fastening for stationary handles of scrap-

er-bowls, and they also, in connection with sliding handles and a revolving bowl, serve a very useful purpose, as has been set forth in this specification.

5 We have described the best mode of constructing the loops and other parts of our invention; but we do not limit ourselves to the special form of the parts.

What we claim as our invention, and desire to 10 secure by Letters Patent, is—

1. A scraper-bowl provided with the loops E, having vertical staying-extensions for bearing against the inner and outer surfaces of the

bowl, said loops serving to receive and permit the handles to slide, and also as a means whereby 15 the handles may with bolts be fastened and held from sliding, substantially as described.

2. A scraper provided with sliding handles, whereby the bowl with the handles is allowed to revolve through the bail of the scraper, substantially as described. 20
